No. 729,590.

PATENTED JUNE 2, 1903.

E. H. HUENEFELD.
ASH OR GARBAGE CAN.
APPLICATION FILED FEB. 27, 1902.

NO MODEL.

UNITED STATES PATENT OFFICE.

ERNST H. HUENEFELD, OF CINCINNATI, OHIO.

ASH OR GARBAGE CAN.

SPECIFICATION forming part of Letters Patent No. 729,590, dated June 2, 1903.

Application filed February 27, 1902. Serial No. 95,970. (No model.)

To all whom it may concern:

Be it known that I, ERNST H. HUENEFELD, of Cincinnati, in the county of Hamilton and State of Ohio, have invented certain new and useful Improvements in Ash or Garbage Cans; and I do hereby declare the following to be a full, clear, and exact description of the invention, such as will enable others skilled in the art to which it appertains to make and use the same.

My invention relates to an improvement in ash and garbage cans, tubs, and other receptacles; and it consists in the details of construction and combination of parts, as will be more fully described, and pointed out in the claims.

In the accompanying drawings, Figure 1 is a view of my improvement. Fig. 2 is a view of the same in vertical section, and Fig. 3 is a transverse sectional view taken through the depending flange of the bottom.

The body of the receptacle 1 is formed of sheet metal corrugated vertically between its ends, the latter being left plain and cylindrical, as shown. The metal of the body, formed by fluting or corrugating same, projects outwardly, as shown at 3, in planes beyond the end sections 2, so that said end sections are of less diameter than the diameter 30 of the body at the apexes of the ribs 3.

The two ends of the sheet comprising the body are bent to form interlocking hooks, which when engaged and locked by upsetting the interlocking ends form a double seam 35 which not only adds rigidity to the body, but also makes a liquid-proof joint. Secured in the upper end of the body thus formed is the reinforcing ring or collar 4. This collar is preferably made of wrought metal of a diameter to snugly fit within the upper plain end 40 of the receptacle, or, if desired, may be of sheet metal folded or doubled upon itself to give it the stiffness and rigidity necessary for it to possess in order to withstand the usage 45 to which an article of this character is subjected in dumping the contents into a wagon, and in either event this ring is provided at a point between its ends with an outwardly-projecting rib or bead 5, which latter rests 50 on the upper edge of the body 1 and also forms a seat for the depending flange of the cap or cover. This reinforcing-ring is secured

in place by bolts or rivets, preferably the latter; but as the rib or bead 5 rests on the upper end of the body of the receptacle the 55 strain is all taken by the bead and is not transmitted to the rivets.

7 represents the bottom. This bottom is slightly dished on its upper surface and is provided at its periphery with an inwardly 60 and downwardly projecting extension 8, the periphery of the shoulder 9, formed by bending inwardly and downwardly, fitting closely within the plain lower end and abutting upwardly against the shoulders 10, formed by 65 the inwardly-projecting ribs produced by corrugating the body.

The depending portion of the extension 8 is by reason of the inward bend given thereto somewhat removed from the inner face of 70 the body, and the annular space between flange 8 and the body is filled by the reinforcing ring or collar 11. This ring or collar 11 is similar to the ring or collar 4 and is so constructed that its upper edge rests under 75 and forms a seat for the shoulder 9 of the bottom, while its bead or rib 13 rests under the lower edge of the body. Hence by securing the reinforcing ring or collar in a position 80 under the bottom and between the depending portion of the extension 8 of the bottom and the body of the receptacle a solid and substantial seat for the latter is formed, and when the parts are galvanized a liquid-proof joint or closure is formed. This reinforcing 85 ring or collar projects below the body of the can sufficient to receive all the wear and rough usage and is secured in place by rivets or bolts 14 passing through the plain end of the body and the ring, and, if desired, also 90 through the depending portion of the extension 8 of the bottom.

With the parts thus constructed and connected and subsequently galvanized to solder all the joints a compact, strong, and durable 95 receptacle is formed, which is admirably adapted for holding ashes or garbage, and by providing the flanged or beaded rings or collars at the top and bottom all the wear or rough usage is borne by these rings.

It is evident that many slight changes might be resorted to in the relative arrangement of parts herein shown and described without departing from the spirit and scope of my in-

vention. Hence I would have it understood that I do not wish to limit myself to the exact construction of parts herein shown and described; but,

5 Having fully described my invention, what I claim as new, and desire to secure by Letters Patent, is—

1. An article of manufacture comprising a hollow body, a bottom having an inwardly and downwardly projecting extension forming a peripheral shoulder on said bottom, shoulders in the body against which the peripheral shoulder on the bottom bears and a supporting-ring inserted between the lower 15 end of the body and the depending portion of the extension on the bottom, said supporting-ring bearing against the peripheral shoulder on the bottom.

2. An article of manufacture comprising a 20 body portion, a bottom having a portion extending inwardly and downwardly and forming a peripheral shoulder on said bottom and a ring or collar filling the space between said body and depending portion and forming a 25 seat on which the peripheral shoulder of the bottom rests.

3. An article of manufacture consisting of a body of general cylindrical form, a bottom having a peripheral portion extending inwardly and downwardly and forming a peripheral shoulder on the bottom, and a ring or collar interposed and filling the space be-

tween said peripheral portion and body and projecting below both.

4. An article of manufacture comprising a 30 body having a plain lower end, a bottom having a peripheral portion extending inwardly and downwardly and forming a peripheral shoulder in said bottom and a ring or collar interposed and filling the space between said 40 peripheral portion of the bottom and the lower end of the body and provided with a bead or rib which rests against the lower end of the body.

5. An article of manufacture comprising a 45 body having plain ends and corrugated between its ends, a bottom having an inwardly and downwardly projecting extension and forming a peripheral shoulder on the bottom, said peripheral shoulder bearing against the 50 internal shoulders formed by the lower ends of the corrugations in the body, and a ring or collar secured to the body filling the space between the lower end of the body and the depending portion of the extension on the 55 bottom and forming a seat for the shoulder on the bottom.

In testimony whereof I have signed this specification in the presence of two subscribing witnesses.

ERNST H. HUENEFELD.
